UNITED STATES PATENT OFFICE.

FREDERICK A. ROEDER, OF CINCINNATI, OHIO, ASSIGNOR, BY MESNE ASSIGNMENTS, TO THE UNITED STATES TORSION BALANCE AND SCALE COMPANY, OF JERSEY CITY, NEW JERSEY.

TORSIONAL PIVOT-BALANCE.

SPECIFICATION forming part of Letters Patent No. 340,006, dated April 13, 1886.

Application filed April 11, 1884. Serial No. 127,524. (No model.)

To all whom it may concern:

Be it known that I, FREDERICK A. ROEDER, a citizen of the United States, residing at Cincinnati, Ohio, have invented new and useful 5 Improvements in Torsional Pivot-Balances, of which the following is a specification.

My invention relates to "torsional pivot" balances or scales in which the pivotal bearings of the beam and scale-pans consist of 10 metal supports acting torsionally between holding-abutments, and is in the nature of an improvement upon Letters Patent No. 262,907, granted to me August 15, 1882. In said Letters Patent I described the use of "stretched 15 metallic wires" acting torsionally, which, as illustrated in the drawings therein, were wires of circular section. In the use of wires of circular section a practical difficulty exists, increased in larger balances employed in weighing heavy bodies in respect to the mode of securing 20 the wires in their fastenings, the circular form being difficult to properly secure against the "twisting" action of constant use. This difficulty is of course magnified in larger scales, 25 where the "wire" is enlarged into a metallic rod and used at relatively shorter "reach," owing to the increased leverage of torsional action against the holding power of the fastenings, and as the metal employed is usually 30 steel or some metal admitting a high tempering to secure elasticity, it is not desirable to "square" the ends or places where the holding devices are attached, and still less so to flatten and pierce them for rivets, as such 35 changes involve a loss of elasticity and strength, seriously impairing the proper action of the balance by reason of the necessity of heating such ends as a condition of the squaring operation. Moreover, even the heat employed in soldering or brazing affects the temperature injuriously, and it is often impossible to obtain a perfectly-secure fastening in holding 40 the circular wire against torsional strains by solder applied to its cylindrical surface. I 45 have found a remedy for these difficulties in the employment of wires or rods of angular or elongated cross-section, which, while possessing all the torsional advantages of cylindrical

wires, admit being secured in holding-sockets of corresponding form.

In carrying out my present invention I do not confine myself to any particular form of cross-section for such torsional pivots, since a pivot having a cross-section of any geometric figure (other than circular) will serve the 55 purpose in view.

In the drawings herewith illustrating my invention, I have shown in Figure 1 a perspective view of the supporting-frame of the central pivots of a double-beam scale. Fig. 2 60 is a cross-sectional view of the pivotal wire in its containing-socket. Fig. 3 is a perspective view of one of the terminal frames. Fig. 4 is a cross-section of a triangular pivotal wire in its socket, and Fig. 5 exhibits a few cross-sections of other forms of pivotal wires which may be employed in carrying out my invention.

For the purposes of present description I have shown in the drawings a supporting-frame for the central pivots of a double-beam scale, consisting of two side standards, A A, and intermediate cross-braces, B B. Between the standards, in parallel horizontal lines, are stretched the pivotal wires a a, that sustain 75 the scale-beams b b. The upper ends of the standards A are recessed by an open slot, s, corresponding with the cross-section of the pivotal wire employed. Thus, if a wire of square section is employed, as in Fig. 1, the 80 recess is rectangular of a corresponding width; or, if a wire of angular section is employed, the recess is formed to a corresponding angle, as in Fig. 4. The apertures at e, for the passage of the lower wire through the standards 85 A, are similarly formed to accommodate the wire employed. In practice but a single wire is used, the ends being brought together and secured at the side of one of the standards, as at s', Fig. 1.

In the case of the terminal frames F, Fig. 3, open slots at the upper and lower ends of the vertical posts f serve to engage the wire, the ends of which are secured at the side of one of the posts, as before, and the wires are 95 secured in correspondingly-shaped notches in

beams *b*. The mode of securing the scale-beams *b* to the pivotal supports is similar, a suitably-formed slot or recess being formed in the under side of the beam or in the collars or washers employed in clamping the wire thereto.

It will be readily perceived that the sides of the recesses or apertures form abutments, which hold the pivotal wires against torsional strains, and that no other fastening is required. The wire may therefore be at once placed in position and stretched without any manipulation affecting its temper or elasticity, and that it will be securely and far more durably retained in such position than by soldering. It will also be obvious that these advantages may be attained by a wire having one or any number of plane faces in its peripheral surface.

I claim as my invention and desire to secure 20 by Letters Patent—

1. In a torsional pivot-balance, in combination with the beam, a pivot of other than circular cross-section, tensioned between holding-abutments and secured to the beam in correspondingly-formed sockets, whereby the pivot is held by its engagement in said sockets without other fastening against rotation, as set forth.

2. The combination, in a weighing-balance, of pivot-holding abutments having sockets, as 30 described, duplicate scale-beams suitably connected, and a single wire of other than circular cross-section stretched and returned between the holding-abutments in parallel lines, constituting fulcrum-pivots for the duplicate beams, and engaging the beams and holding-abutments in correspondingly formed sockets, forming a rigid connection against rotation therein, substantially as set forth.

3. In a torsional pivot-balance, in combination with the balance-beam, a terminal pendulum frame having plane-faced sockets at top and bottom, and a torsional pivot of other than circular cross-section stretched upon the frame and engaging in said sockets by means of its 40 said plane face or faces, substantially as set forth.

In testimony whereof I have hereunto set my hand in the presence of two subscribing witnesses.

FREDERICK A. ROEDER.
